UNITED STATES PATENT OFFICE

GEORGES EZBELENT AND ROGER EZBELENT, OF PARIS, FRANCE

AUTOMATIC SPACING DEVICE FOR PLAITING MACHINES

Application filed June 28, 1926, Serial No. 119,212, and in France January 28, 1926.

In the operation of plaiting machines, it is often desired to leave blank or unplaited areas in the goods between the areas which are plaited, and for this purpose the rollers 5 are rotated for a certain time without the formation of plaits. To produce this result in the known machines, the machine must be stopped, and the rollers are then turned by the usual means such as a ratchet and pawl 10 device, or the like, or in certain types of machines which are provided with automatic spacing means for producing the blank areas, the machine is allowed to make a certain number of revolutions while the plaiting device has been made inoperative; in this latter case a small amount of the fabric is drawn by the rollers during their intermittent movement at each revolution of the machine until the requisite blank area is obtained. 15 But in all cases it is necessary to stop the machine or the plait forming device, and there is danger of producing glossy marks upon the goods, when the latter are made of certain fabrics, by reason of the intermittent motion of the rollers.

The present invention has for its object a device whereby this spacing will be automatically obtained at a given time, and will also be given a variable width, without stopping the rollers during the travel of the unplaited fabric. The said device is chiefly characterized in that the lower roller is adapted to be rotated, independently of the usual rotation for the formation of plaits, 30 by means of a one way device, e. g. a pawl and ratchet device, the actuating member whereof (for instance the pawl) is adapted to be given a rocking motion of variable amplitude between the formation of two consecutive plaits.

In the appended drawing which is given solely by way of example:

Fig. 1 is an elevation of the device according to the invention.

Fig. 2 is an elevation of a cam with removable bosses for the control of the one way driving device for the roller.

Fig. 3 is a partial section on the line A—A of Fig. 2.

Fig. 4 is a section on the line B—B of Fig. 3.

Fig. 5 is an elevational view of one side of a plaiting machine.

Fig. 6 is an elevational view of the other side of the same machine provided with the device according to the invention.

In the construction illustrated, 1 and 2 are the two rollers of the plaiting machine. Said rollers are turned by the usual means for forming plaits such as a ratchet wheel *a* mounted on one side of the lower roller 2 and a cooperating pawl *b* connected by the links *c*, *d*, *e*, to the knife-carrier *f*. Said knife-carrier is moved towards and away from the rollers by means of links *g*, disposed on either side of the machine and pivoted at *h*, one end of said links being connected to the knife-carrier *f* and the other end of said links being guided in cams *j* rotating on the main driving shaft *k* of the machine. The means above described are already known and form no part of the present invention.

Another ratchet wheel *l* is secured to the other side of the lower roller 2 and coaxially therewith is also mounted a pawl-carrier 4. The arm 6, pivoted on the pin 7, actuates the said pawl-carrier through the medium of the link 5. The rocking motion of the said arm is obtained by means of the cam or eccentric 8 mounted on the shaft *k* and towards which the said arm is constantly urged by the spring 10, and upon which it is adapted to roll through the medium of the roller 9. The link 5 makes contact with a cam or eccentric 11 against which it is urged by the spring 12. The rotation of the said cam displaces the pivoting fulcrum of the said link upon the arm 6, whereby the length of the lever arm, and hence the amplitude of motion of the pawl-carrier 4, is changed. The claw 13, pivotally supported by a fixed pin 14, co-operates with a hook 16 secured to or integral with the arm 6, and the free end of an extension of the claw is brought into contact—by the spring 15—with a rotary disc 18 provided with bosses 17 and to which a continuous or intermittent rotation is imparted. When none of the said bosses lowers the claw 13, the latter will engage the hook 16, and the arm 6 is thus held. If one of the bosses acts upon the claw 13, the latter will be removed from the

100

hook 16 against the action of the spring 15, thus affording the free rocking motion of the arm 6, so that the roller 2 is rotated by the ratchet and pawl device, thus leaving a blank area in the plaited work.

5 The disc 18 provided with the bosses 17 controls at the proper time the release of the arm 6; the said disc is preferably constructed as shown in Figs. 2, 3 and 4. The disc 10 18 has formed therein peripheral recesses 19, in variable number, in which are movable rollers 17 forming the removable bosses. Each of the said rollers is mounted on a shaft 20 and is axially movable therewith; the said 15 shaft has an enlarged part 21 having the same cross section as the slot 22 in the wall 23. A spring 24, bearing at one end upon the wall 23 and at the other upon the inner face of a cap 25 mounted on the end of the shaft 20, urges the roller 17 into contact with the wall 23. When one of the enlarged parts 21 has been turned into coincidence with the slot 22, the corresponding roller will make contact with the wall 23, it being withdrawn into its 25 inoperative position relatively to the claw 13.

Should all of the rollers 17 on the disc 18 be in the inoperative position, no automatic spacing effect will be produced, but if one or more determined rollers are moved into their 30 operative position, one or more spacing effects are thus produced at the proper time and at the desired place upon the plaited goods.

The unplaited areas resulting therefrom may be made wider or narrower, by varying 35 the fulcrum of the link 5 on the arm 6, this being obtained by the rotation of the cam 11.

Obviously, the present invention is not limited to the hereinbefore described form of construction which is given solely by way 40 of example, and it is susceptible of various modifications in detail without departing from the principle of the invention.

Having now described our invention, what we claim as new and desire to secure by Letters Patent is:

45 1. In a plaiting machine, the combination with a plait producing mechanism adapted to rotate intermittently one roller of the machine for spacing two consecutive plaits from each other, of means for imparting to said roller an additional rotative movement and means for adjusting the amplitude of said additional rotative movement quite independently from the plait producing mechanism.

50 2. In a plaiting machine, the combination with a plait producing mechanism adapted to rotate intermittently one roller of the machine for spacing two consecutive plaits from each other, of means for imparting to said roller an additional rotative movement consisting of a one way driving device, the driven member of which is operatively connected to said roller and the driving member 55 of which, quite independent from the plait

producing mechanism, comprises a link, an adjustable axle on which said link is adapted to rotate, means independent from the plait producing mechanism for imparting to said axle and to said link a reciprocating movement and means for causing said reciprocating means to be inoperative.

5 70 3. In a plaiting machine, the combination with a plait producing mechanism adapted to rotate intermittently one roller of the machine for spacing two consecutive plaits from each other, of means for imparting to said roller an additional rotative movement consisting of a one way driving device, the driven member of which is operatively connected to said roller and the driving member of which, quite independent from the plait producing mechanism, comprises a link, an adjustable axle on which said link is adapted to rotate, a pivoting arm, means on said arm adapted to carry said axle of said link adjustably along said arm, means for pivoting said arm and means for stopping the pivoting movement of said arm.

80 75 4. In a plaiting machine, the combination with a plait producing mechanism adapted to rotate intermittently one roller of the machine for spacing two consecutive plaits from each other, of means for imparting to said roller an additional rotative movement consisting of a one way driving device, the driven member of which is operatively connected to said roller and the driving member of which, quite independent from the plait producing mechanism, comprises a link, an adjustable axle on which said link is adapted to rotate, a pivoting arm, means on said arm adapted to carry said axle of said link adjustably along said arm, a cam adapted to move said axle of said link along said arm, means for pivoting said arm and means for stopping the pivoting movement of said arm.

90 85 5. In a plaiting machine, the combination with a plait producing mechanism adapted to rotate intermittently one roller of the machine for spacing two consecutive plaits from each other, of means for imparting to said roller an additional rotative movement consisting of a one way driving device, the driven member of which is operatively connected to said roller and the driving member of which, quite independent from the plait producing mechanism, comprises a link, an adjustable axle on which said link is adapted to rotate, a pivoting arm, means on said arm adapted to carry said axle of said link adjustably along said arm, means for pivoting said arm, a hook on said arm, and a rocking claw adapted to engage and hold said hook 100 at will.

105 110 6. In a plaiting machine, the combination with a plait producing mechanism adapted to rotate intermittently one roller of the machine for spacing two consecutive plaits from 115 120 125 130

each other, of means for imparting to said roller an additional rotative movement consisting of a one way driving device, the driven member of which is operatively connected to
5 said roller and the driving member of which, quite independent from the plait producing mechanism, comprises a link, an adjustable axle on which said link is adapted to rotate, a pivoting arm, means on said arm adapted
10 to carry said axle of said link adjustably along said arm, means for pivoting said arm, a hook on said arm, a rocking claw adapted to engage and hold said hook, and a rotary cam carrying disc adapted to control the engagement and the disengagement of said claw with said hook.

7. In a plaiting machine as claimed in claim 6, the further feature residing in that the cams of said rotary disc are selectively
20 mounted on the same so as to be moved into an operative position for which they encounter the said claw and into an inoperative position, each cam being provided with an enlarged stop part adapted to engage and pass
25 through a corresponding slot in said disc and with a spring whereby each cam is adapted to be maintained in either of its two positions.

In testimony whereof we have signed our
30 names to this specification.

GEORGES EZBELENT.
